FOLDING STOOL

Filed Feb. 16, 1928

2 Sheets-Sheet 2

UNITED STATES PATENT OFFICE.

WILLIAM H. ROMIG, OF LEBANON, PENNSYLVANIA, ASSIGNOR OF ONE-HALF TO
CLAUDE WEIDLER, OF LEBANON, PENNSYLVANIA.

FOLDING STOOL.

Application filed February 16, 1928. Serial No. 254,837.

The present invention relates to improvements in folding stools and has for its principal object to provide a stool that can be readily and easily set up in position for use whenever necessary, the same being equally as well folded into compact form when not in use, thus enabling the stool to be stored away in any desirable place without occupying much space.

10 A further object of the invention is to provide a folding stool which is simple in construction, inexpensive, strong and durable and further well adapted to the purpose for which it is designed.

15 Other objects and advantages of the invention will become apparent from the following description when taken in connection with the accompanying drawings.

In the accompanying drawings wherein 20 like reference characters indicate corresponding parts throughout the several views:

Figure 1 is a side elevation of the folding stool embodying my invention showing the same in its assembled position.

25 Figure 2 is an end elevation thereof.

Figure 3 is a side elevation showing the stool in its folded position.

Figure 4 is an edge elevation of the folded stool.

30 Figure 5 is an enlarged longitudinal sectional view through one of the hubs showing one pair of the arms and legs in an extended position, the other pair being shown in their folded position, and

35 Figure 6 is a detail sectional view showing the manner in which one corner of the seat is secured to the upper end of the adjacent arm.

In the drawings wherein for the purpose of illustration is shown the preferred embodiment of my invention, the numeral 1 designates generally my improved folding stool, the same comprising a pair of hub members designated generally by the numerals 2 and 3, respectively.

40 Each of these hub members includes a pair of spaced rectangular shaped plates 4 and 5 between which is secured at the intermediate portion thereof a wooden filler block 6, and as is more clearly shown in Figure 5, the upper edges of this block are beveled as illustrated at 7. This block is rigidly secured between the plates of each of the hub members and is disposed directly below the upper edges of the plates.

45 A pair of transversely extending pivots 8

and 9 are arranged between the spaced plates of each of the hub members inwardly of the ends of the plates. A pair of leg members 10 and 11 is associated with each of the hub members and the upper end of each of the leg members has secured on the opposite sides thereof the metallic plates 12 and portions of these plates project beyond the upper extremities of the leg members for pivotal engagement with the respective pivots 8 and 9 as is clearly illustrated in Figure 5 whereby said leg members are adapted for vertical swinging movement.

50 A pair of seat supporting arms designated by the numerals 13 and 14 respectively is also associated with each of the hub members and the lower end of each of the seat supporting arms has secured on the opposite side faces thereof the metallic plates 15 similar to the plates 12 for engagement with the respective pivot pins whereby said arms are also adapted for vertical swinging movement. The manner in which the pivoted legs and seat supporting arms function will be presently described.

55 The upper end of each arm is bifurcated as illustrated at 16 and secured on the outer side face of the bifurcated upper end of each arm is the metallic plate 17 that is formed with a longitudinal slot 18 as more clearly disclosed in Figure 6.

60 The canvas seat 19 is formed at its respective ends with the roller receiving loops 20, the roller being designated by the numerals 21, and an elongated rod 22 extends centrally through each roller and is of greater length than the roller.

65 One end of the rod is formed with a head 23, while the other extremity is threaded. The ends of the rod are spaced with respect to the adjacent ends of each roller so that the outwardly projecting portions of the rods will be received within the bifurcated upper ends 16 of the supporting arms 13 and 14. The heads 23 will engage with the metallic plates 17 of one pair of the arms, while thumb nuts 24 are threaded on the threaded extremities 25 of the rods and engage the metallic plates arranged on the upper bifurcated ends of the other pair of arms for positively securing the seat 13 on the upper ends of the arms when the stool is assembled for use. Of course when not in use, the seat is removed from engagement with the upper bifurcated ends of the arms and then the seat

may be rolled up and stored away in a relatively small space.

For the purpose of holding the hubs 2 and 3 in proper spaced relation, I provide the complementary brace bars 26 and 27, respectively, the same being pivotally connected together at their inner opposed ends. The outer ends of these brace bars are pivotally connected to suitable brackets that extend laterally from the outer face of the innermost plate 5 of each hub member, and for the purpose of limiting the swinging movement of these brace bars in one direction, there is formed in the bar 27 a notch 28 with which 10 cooperates the laterally extending lug 29 carried by the brace bar 26 as is clearly shown in Figure 1. Thus when the brace bars are disposed in horizontal alinement, the hub members 2 and 3 are spaced with respect to 20 each other so that the seat 13 may be properly attached to the upper ends of the arms 13 and 14, and for the purpose of maintaining the seat supporting arms in their proper position, there is provided additional braces 25 30 and 31 that are pivotally connected together at their inner opposed ends, the outer ends of the braces 30 and 31 being pivotally secured to the intermediate portions of the arms and the adjacent leg members as clearly 30 shown in Figure 2. These braces are also formed with complementary means to limit the swinging movement of the same in one direction similar to the lug and notch associated with the spacing members for the hubs. 35

Similar braces 32 and 33 are associated with each pair of leg members whereby when 40 said brace members 32 and 33 are disposed in horizontal alinement with each other, the legs will be disposed in diverging relation, and will be properly supported against inward swinging movement.

When the parts are assembled in position so that the stool 1 may be occupied, it will be observed that that the free lower corners of 45 the arms will engage with the respective beveled faces 7 of the filler blocks 6 in each of the hub members and the various braces will maintain the pivoted members in their stool forming position.

When not in use, the stool may be folded into a compact form as shown in Figures 3 and 4 and it will be observed that the leg members and the arms of each hub will be disposed in vertical substantially abutting 55 relation.

When the brace members 26 and 27 are folded together, this will result in the hub members 2 and 3 being brought into close relation with respect to each other and thus the 60 stool when folded in this manner may be stored away in any convenient place without

occupying any considerable amount of space.

A folding stool of the above mentioned character can be carried in an automobile and used whenever necessary and can also be 65 easily and readily set up for use without the necessity of having to employ any tools or the like. Furthermore a folding stool of this character will be strong and durable, and yet very inexpensive.

While I have shown the preferred embodiment of my invention, it is to be understood that various changes in the size, shape and arrangement of parts may be resorted to without departing from the spirit of the invention and the scope of the appended claims.

Having thus described the invention, what I claim as new and desire to secure by Letters Patent is:—

1. A folding stool comprising a pair of 80 hubs, each hub including a pair of spaced plates, a filler block arranged between each pair of spaced plates, means for holding the hubs in spaced relation, a pair of legs pivoted at their upper ends between the spaced plates 85 of each hub on opposite sides of the filler block, a pair of seat supporting arms pivoted at their lower ends between the spaced plates of each hub, the pivoted ends of the arms adapted to engage the filler block for limiting the swinging movement of the arms in one direction, bracing means between the legs and the arms for maintaining the same in an operative position, and a seat supported on the upper ends of the arms.

2. A folding stool comprising a pair of hub members, each including a pair of spaced plates, a filler block arranged between each pair of spaced plates, transverse pivot pins extending between the plates on opposite 100 sides of the filler block, means for holding the hub members in spaced relation, pairs of legs, plates secured on opposite sides of the upper end of each leg, and being operatively connected to the respective transverse 105 pivot pins whereby said legs are capable of vertical swinging movement between the plates of the respective hub members, a pair of vertically swinging seat supporting arms for disposition between the first mentioned 110 plates of each hub member, plates secured on the opposite sides of the lower ends of the arm members for respective connection with the transverse pivot pins, the pivoted ends of the arms adapted to engage the filler block 115 for limiting the swinging movement of the arms in one direction, bracing means between the legs and the arms for maintaining the same in an operative position, and a seat supported on the upper ends of the arms.

In testimony whereof I affix my signature.

WILLIAM H. ROMIG.
